UNITED STATES PATENT OFFICE.

GEORGE GRAFF, OF NEW YORK, N. Y., ASSIGNOR TO GRAFF, WASHBOURNE & DUNN, A CORPORATION OF NEW YORK.

DESIGN FOR A SUPPORT FOR LAMPS AND THE LIKE.

Application filed February 8, 1921. Serial No. 443,471. Term of patent 14 years.

To all whom it may concern:

Be it known that I, GEORGE GRAFF, a citizen of the United States, residing at New York city, county of Bronx, State of New York, have invented a new, original, and ornamental Design for a Support for Lamps and the like, of which the following is a specification.

This invention relates to a new, original and ornamental design for a support, useful for a variety of purposes as for supporting electric lights or the like, and the invention consists in the peculiar shape of the same

substantially as shown in the accompanying drawing forming a part of this specification, in which the figure is an elevation.

The design consists in the peculiar shape of the support having the base A, standard B of smaller diameter and housing C.

I claim.

The ornamental design for a support for lamps and the like as shown and described.

In testimony whereof, I have hereunto set my hand.

GEORGE GRAFF.
